UNITED STATES PATENT OFFICE.

LOUIS HICKS, OF BATAVIA, OHIO.

STEAM-ENGINE.

SPECIFICATION forming part of Letters Patent No. 743,282, dated November 3, 1903.

Application filed April 10, 1903. Serial No. 151,965. (No model.)

To all whom it may concern:

Be it known that I, LOUIS HICKS, a citizen of the United States, residing at Batavia, in the county of Clermont and State of Ohio, have invented certain new and useful Improvements in Steam-Engines, of which the following is a specification.

The object of my invention is to provide an improved compound steam-engine of simple construction and economical operation in which condensation of the steam in the cylinders during admission and expansion is prevented and in which steam at high or low pressure may be used and the full expansive force of the steam obtained without loss from condensation.

In the drawings, Figure 1 is a longitudinal section of compound-engine cylinders and their operative parts embodying my invention, and Fig. 2 a cross-section on line 2 2 of Fig. 1.

Reference-letters A and B denote, respectively, the high and low pressure cylinders of a compound engine; C, a steam-chamber inclosing cylinders A and B; D, pistons operating in cylinders A; E, pistons operating in cylinders B; F, a valve for cylinders A; G, a valve for cylinders B, and H a shaft driven by cylinders A and B and pistons D and E.

The high-pressure cylinders A are open at one end and are mounted in alinement with each other with their closed ends adjacent. They are preferably formed in one casting and joined together at their inner closed ends by cross-pieces *a* and stuffing-box *a'*, so as to leave an open space *a*² between them. Lugs *a*³ serve to hold them in position in chamber C. The low-pressure cylinders B are also open at one end and mounted in alinement with each other with their closed ends adjacent. They are also preferably in one casting and joined together at their inner closed ends by cross-pieces *b* and stuffing-box *b'*, so as to leave an open space *b*² between them. Lugs *b*³ serve to hold them in position in chamber C.

Chamber C may be of any desired shape. It incloses cylinders A and B with an open space *c* around them and is provided with an inlet-pipe *c'* for a steam-supply.

Pistons D are mounted on a single piston-rod *d*, passing through stuffing-box *a'* be-

tween cylinders A and through stuffing-box *c*² in the wall of chamber C. The position of pistons D on rod *d* is such that when one is near the inner end of its cylinder the other is near the outer end of its cylinder, and vice versa, with the operative side of each piston turned toward the inner closed end of its cylinder. On their inoperative sides pistons D are hollowed out, as indicated in Fig. 2. Pistons E are also mounted on a single piston-rod *e*, passing through stuffing-box *b'* between cylinders B and through stuffing-box *c'* in the wall of chamber C. Their positions relatively to each other are the same as pistons D, and they are similarly hollowed out on their inoperative sides.

Valve F is mounted on valve-seat *f* and is operated by any desired form of valve-gear (not shown) to admit steam from the space *c* in chamber C to cylinders A and exhaust cylinders A into exhaust-chamber *a*⁴ through ports *a*⁵ to cause reciprocation of pistons D and rod *d*.

The exhaust-chamber *a*⁴ is connected by a pipe *a*⁶ with supply-chamber *b*⁶ for cylinders B, so that the steam exhausted from cylinders A is conveyed to the supply-chamber for cylinders B.

Valve G is mounted on valve-seat *g* and is operated by any desired form of valve-gear (not shown) to admit steam from chamber *b*⁶ to cylinders B and exhaust cylinders B into exhaust-chamber *b*⁴ through ports *b*⁵ to cause reciprocation of pistons E and rod *e*.

The shaft H is mounted in any suitable bearings and is provided with crank-arms *h*, which are preferably one hundred and eighty degrees apart, as indicated in Fig. 2. Crank-arms *h* are connected with piston-rods *d* and *e* by means of rods *h'* and any suitable form of cross-heads. (Not shown.) The operative power of the engine may be taken from shaft H by a pulley or other suitable means.

In operation the live steam is admitted to chamber C through inlet-pipe *c'* and completely surrounds the cylinders A and B and their operative and connecting parts. Valve F admits the live steam from chamber C into cylinders A alternately and exhaust cylinders A alternately into exhaust-chamber *a*⁴. This causes the pistons D and piston-rod *d* to reciprocate and rotate shaft H. After a par-

tial expansion in cylinders A the steam is thus exhausted into chamber a^4 , whence it passes through pipe a^6 to supply-chamber b^6 for cylinders B. Valve G operates to admit 5 the exhaust-steam from chamber b^6 to cylinders B alternately and exhaust cylinders B alternately into exhaust-chamber b^4 , thus obtaining the complete expansion of the steam to reciprocate pistons E and piston-rod e and 10 rotate shaft H. It will be noted that the steam in chamber C completely surrounds cylinders A and B and their operative and connecting parts, so that the live steam from the boiler has access to the outer walls of cylinders A 15 and B, to their inner heads, to their open ends, to the piston-heads, to the valve-chest for cylinder A, and to the walls of the supply-chamber for cylinders B and serves to heat these surfaces to and maintain them at the 20 temperature of the boiler-steam. When they are so heated, the working steam admitted to the cylinders comes in contact with the surfaces of the steam-passages and the piston and cylinderheads heated to its own temperature 25 by compression and the conduction of heat to these surfaces through the metal from the live steam in contact with the opposite surfaces, and since the temperatures of these surfaces and the working steam are 30 the same no condensation can take place. As admission continues to the point of cut-off and the piston advances the working steam comes in contact with the surfaces of the cylinder-walls already heated to the temperature 35 of the prime steam by contact with the prime steam in the open end of the cylinder and by conduction of heat through the cylinder-walls from the live steam surrounding the cylinders, and consequently during this period 40 no condensation can occur.

Beneficial results can be obtained with steam in chamber C of any degree of temperature above that of the exhaust; but it is preferable to use the steam at a temperature equal 45 to or greater than that supplied to the cylinders A.

After cut-off and during expansion to the end of the stroke the working steam is in contact with surfaces heated by the prime steam 50 to its own temperature, as above described, and these surfaces during expansion continue at a higher temperature than the temperature of the expanding steam, and therefore no condensation occurs during the expansion period, but, on the contrary, the 55 tendency is to superheat the expanding steam. The steam-surfaces being heated and dry at the end of the stroke no loss of heat by re-evaporation like that which occurs in the ordinary 60 engine will take place during exhaust.

The working steam during expansion and exhaust being of lower temperature than the surfaces inclosing it will to a slight degree reduce the temperature of these surfaces at 65 each stroke; but this slight loss of heat will be restored each stroke to these surfaces by conduction of heat through the metal from

the live steam in the spaces and by the live steam following the pistons through the open ends of the cylinders during the return stroke. 70 This restoration of heat to the surfaces occurring after each stroke gives to the steam-surfaces the temperature of the prime steam for the admission and expansion of the next stroke and prevents a low range of temperature 75 from being established like that to which the working steam is subjected in the ordinary engine. Under this condition of admitting and expanding the steam in contact with surfaces of an equal or higher temperature 80 steam of any pressure may be used and expanded to any degree without loss from cylinder condensation. This restoration of heat to the working steam-surfaces by conduction of heat from the steam in the steam-spaces 85 and by the live steam in the open ends of the cylinders will cause a corresponding condensation in the outside chamber and open ends of the inside cylinders, and the water produced by this condensation, together with 90 the water produced by condensation arising from radiation of heat from the outside chamber, will have a temperature but slightly lower than that of the prime steam and will collect in the lowest part of the outside chamber 95 and will be returned to the boiler by a drain pipe or pump, and the heat contained in this water will not be lost. The pressure of the live steam on the piston-heads D and E being equal and in opposite directions is 100 neutralized.

While I have illustrated and described the preferred form of application of my invention, this is capable of many variations without departing from the spirit of the invention. I therefore do not wish to be confined to this particular form of apparatus; but 105

What I claim as new, and desire to secure by Letters Patent, is—

1. In a steam-engine, the combination of 110 two high-pressure cylinders, each having a closed and an open end; pistons in the high-pressure cylinders; two low-pressure cylinders, each having a closed and an open end; pistons in the low-pressure cylinders; means 115 for admission and exhaust for the closed ends of the high-pressure cylinders; means for admitting the exhaust from the high-pressure cylinders to the closed ends of the low-pressure cylinders, and exhausting the low-pressure cylinders; a steam-passage connecting the open ends of the high-pressure cylinders; a steam-passage connecting the open ends of the low-pressure cylinders; and means for admitting high-temperature steam to the open 120 ends of the high and low pressure cylinders, substantially as specified.

2. In a steam-engine, the combination of 125 two high-pressure cylinders, each having a closed and an open end; pistons in the high-pressure cylinders, mounted to take their operative strokes alternately; two low-pressure cylinders, each having a closed and an open end; pistons in the low-pressure cylinders,

mounted to take their operative strokes alternately; means for admission and exhaust for the closed ends of the high-pressure cylinders; means for admitting the exhaust from the high-pressure cylinders to the closed ends of the low-pressure cylinders, and exhausting the low-pressure cylinders; a steam-passage connecting the open ends of the high-pressure cylinders; a steam-passage connecting the open ends of the low-pressure cylinders; and means for admitting high-temperature steam to the open ends of the high and low pressure cylinders, substantially as specified.

3. In a steam-engine, the combination of two high-pressure cylinders, each having a closed and an open end, mounted in alinement with each other with their closed ends adjacent; pistons in the high-pressure cylinders, carried by a single piston-rod passing through the closed ends of the cylinders; two low-pressure cylinders, each having a closed and an open end, mounted in alinement with each other with their closed ends adjacent; pistons in the low-pressure cylinders, carried by a single piston-rod passing through the closed ends of the cylinders; means for admission and exhaust for the closed ends of the high-pressure cylinders; means for admitting the exhaust from the high-pressure cylinders to the closed ends of the low-pressure cylinders, and exhausting the low-pressure cylinders; a steam-passage connecting the open ends of the high-pressure cylinders; a steam-passage connecting the open ends of the low-pressure cylinders; and means for admitting high-temperature steam to the open ends of the high and low pressure cylinders, substantially as specified.

4. In a steam-engine, the combination of two high-pressure cylinders, each having a closed and an open end; pistons in the high-pressure cylinders; two low-pressure cylinders, each having a closed and an open end; pistons in the low-pressure cylinders; means for admission and exhaust for the closed ends of the high-pressure cylinders; means for admitting the exhaust from the high-pressure cylinders to the closed ends of the low-pressure cylinders, and exhausting the low-pressure cylinders; and a chamber inclosing the high and low pressure cylinders and forming a steam-space around them, substantially as specified.

5. In a steam-engine, the combination of two high-pressure cylinders, each having a closed inner and an open outer end; pistons in the high-pressure cylinders; two low-pressure cylinders, each having a closed inner and an open outer end; pistons in the low-pressure cylinders; means for admission and exhaust for the closed ends of the high-pressure cylinders; means for admitting the exhaust from the high-pressure cylinders to the closed ends of the low-pressure cylinders, and exhausting the low-pressure cylinders; and a chamber inclosing the high and low

pressure cylinders and forming a steam-space around them, substantially as specified.

6. In a steam-engine, the combination of two high-pressure cylinders, each having a closed inner and an open outer end, mounted in alinement with each other with their inner ends adjacent; pistons in the high-pressure cylinders; two low-pressure cylinders, each having a closed inner and an open outer end, mounted in alinement with each other with their inner ends adjacent; pistons in the low-pressure cylinders; means for admission and exhaust for the closed ends of the high-pressure cylinders; means for admitting the exhaust from the high-pressure cylinders to the closed ends of the low-pressure cylinders, and exhausting the low-pressure cylinders; and a chamber inclosing the high and low pressure cylinders and forming a steam-space around them, substantially as specified.

7. In a steam-engine, the combination of two high-pressure cylinders, each having a closed inner and an open outer end; pistons in the high-pressure cylinders; two low-pressure cylinders, each having a closed inner and an open outer end; pistons in the low-pressure cylinders; a valve and a valve-seat for the high-pressure cylinders; an exhaust-chamber for the high-pressure cylinders; a valve and a valve-seat for the low-pressure cylinders, in communication with the exhaust-chamber; and a chamber inclosing the high and low pressure cylinders, the valve for the high-pressure cylinders, and the exhaust-chamber, and forming a steam-space around them, substantially as specified.

8. In a steam-engine, the combination of two high-pressure cylinders, each having a closed inner and an open outer end, mounted in alinement with each other with their inner ends adjacent, but having a space between them; pistons in the high-pressure cylinders; two low-pressure cylinders, each having a closed inner and an open outer end, mounted in alinement with each other with their inner ends adjacent, but having a space between them; pistons in the low-pressure cylinders; a valve and a valve-seat for the high-pressure cylinders; an exhaust-chamber for the high-pressure cylinders; a valve and a valve-seat for the low-pressure cylinders, in communication with the exhaust-chamber; and a chamber inclosing the high and low pressure cylinders, the valve for the high-pressure cylinders, and the exhaust-chamber, and forming a steam-space around them, substantially as specified.

9. In a steam-engine, the combination of two high-pressure cylinders, each having a closed and an open end; pistons in the high-pressure cylinders, hollowed out on one side; two low-pressure cylinders, each having a closed and an open end; pistons in the low-pressure cylinders, hollowed out on one side; means for admission and exhaust for the closed ends of the high-pressure cylinders;

- means for admitting the exhaust from the high-pressure cylinders to the closed ends of the low-pressure cylinders, and exhausting the low-pressure cylinders; a steam-passage 5 connecting the open ends of the high-pressure cylinders; a steam-passage connecting the open ends of the low-pressure cylinders; and means for admitting high-temperature steam to the open ends of the high and low pressure cylinders, substantially as specified.
10. In a steam-engine, the combination of two high-pressure cylinders, each having a closed and an open end; pistons in the high-pressure cylinders, hollowed out on the inoperative side; two low-pressure cylinders, each having a closed and an open end; pistons in the low-pressure cylinders, hollowed out on the inoperative side; means for admission and exhaust for the closed ends of the high-pressure cylinders; means for admitting the exhaust from the high-pressure cylinders to the closed ends of the low-pressure cylinders, and exhausting the low-pressure cylinders; a steam-passage connecting 15 the open ends of the high-pressure cylinders; a steam-passage connecting the open ends of the low-pressure cylinders; and means for admitting high-temperature steam to the open ends of the high and low pressure cylinders, 20 substantially as specified.
11. In a steam-engine, the combination of two high-pressure cylinders, each having a closed and an open end; pistons in the high-pressure cylinders, hollowed out on one side; 25 two low-pressure cylinders, each having a closed and an open end; pistons in the low-pressure cylinders, hollowed out on one side; means for admission and exhaust for the closed ends of the high-pressure cylinders; 30 means for admitting the exhaust from the high-pressure cylinders to the closed ends of the low-pressure cylinders, and exhausting the low-pressure cylinders; a steam-passage connecting the open ends of the high-pressure cylinders; a steam-passage connecting the open ends of the low-pressure cylinders; and a chamber inclosing the high and low pressure cylinders and forming a steam-space 35 around them, substantially as specified.
12. In a steam-engine, the combination of two high-pressure cylinders, each having a closed inner and an open outer end, mounted in alinement with each other with their inner ends adjacent, but having a space between them; pistons in the high-pressure cylinders, hollowed out on one side; two low-pressure cylinders, each having a closed inner and an open outer end, mounted in alinement with each other with their inner ends adjacent, but having a space between them; pistons in the low-pressure cylinders, hollowed out on one side; a valve and a valve-seat for the high-pressure cylinders; an exhaust-chamber for the high-pressure cylinders; a valve and a valve-seat for the low-pressure cylinders, in communication with the exhaust-chamber; and a chamber inclosing the high and low pressure cylinders, substantially as specified.

sure cylinders, the valve for the high-pressure cylinders, and the exhaust-chamber, and forming a steam-space around them, substantially as specified.

13. In a steam-engine, the combination of two high-pressure cylinders, each having a closed inner and an open outer end, mounted in alinement with each other with their inner ends adjacent; pistons in the high-pressure cylinders, carried by a single piston-rod passing through the closed inner ends of the cylinders; two low-pressure cylinders, each having a closed inner and an open outer end, mounted in alinement with each other with their inner ends adjacent; pistons in the low-pressure cylinders, carried by a single piston-rod passing through the closed inner ends of the cylinders; means for admission and exhaust for the high-pressure cylinders; means for admitting the exhaust from the high-pressure cylinders to the low-pressure cylinders, and exhausting the low-pressure cylinders; and a chamber inclosing the high and low pressure cylinders and forming a steam-space around them, substantially as specified.

14. In a steam-engine, the combination of two high-pressure cylinders, each having a closed inner and an open outer end, mounted in alinement with each other with their inner ends adjacent, but having an open space between them; pistons in the high-pressure cylinders, carried by a single piston-rod passing through the closed inner ends of the cylinders; two low-pressure cylinders, each having a closed inner and an open outer end, mounted in alinement with each other with their inner ends adjacent, but having an open space between them; pistons in the low-pressure cylinders, carried by a single piston-rod passing through the closed inner ends of the cylinders; means for admission and exhaust for the high-pressure cylinders; means for admitting the exhaust from the high-pressure cylinders to the low-pressure cylinders, and exhausting the low-pressure cylinders; and a chamber inclosing the high and low pressure cylinders and forming a steam-space around them, substantially as specified.

15. In a steam-engine, the combination of two high-pressure cylinders, each having a closed inner and an open outer end, mounted in alinement with each other with their inner ends adjacent; pistons in the high-pressure cylinders, carried by a single piston-rod passing through the closed inner ends of the cylinders; two low-pressure cylinders, each having a closed inner and an open outer end, mounted in alinement with each other with their inner ends adjacent; pistons in the low-pressure cylinders, carried by a single piston-rod passing through the closed inner ends of the cylinders; a valve and a valve-seat for the high-pressure cylinders; an exhaust-chamber for the high-pressure cylinders; a valve and a valve-seat for the low-pressure cylinders, located in the exhaust-chamber; and a chamber inclosing the high and low pressure cylinders, substantially as specified.

inders and forming a steam-space around them, substantially as specified.

16. In a steam-engine, the combination of two high-pressure cylinders, each having a closed inner and an open outer end, mounted in alinement with each other with their inner ends adjacent, but having an open space between them; pistons in the high-pressure cylinders, carried by a single piston-rod passing through the closed inner ends of the cylinders; two low-pressure cylinders, each having a closed inner and an open outer end, mounted in alinement with each other with their inner ends adjacent, but having an open space between them; pistons in the low-pressure cylinders, carried by a single piston-rod passing through the closed inner ends of the cylinders; a valve and a valve-seat for the high-pressure cylinders; an exhaust-chamber for the high-pressure cylinders; a valve and a valve-seat for the low-pressure cylinders, located in the exhaust-chamber; and a chamber inclosing the high and low pressure cylinders, the valve for the high-pressure cylinders and the exhaust-chamber, and forming a steam-space around them, substantially as specified.

17. In a steam-engine, the combination of two high-pressure cylinders, each having a

closed inner and an open outer end, mounted in alinement with each other with their inner ends adjacent, but having an open space between them; pistons in the high-pressure cylinders, carried by a single piston-rod passing through a stuffing-box mounted between the closed inner ends of the cylinders; two low-pressure cylinders, each having a closed inner and an open outer end, mounted in alinement with each other with their inner ends adjacent, but having an open space between them; pistons in the low-pressure cylinders, carried by a single piston-rod passing through a stuffing-box mounted between the closed inner ends of the cylinders; a valve and a valve-seat for the high-pressure cylinders; an exhaust-chamber for the high-pressure cylinders; a valve and a valve-seat for the low-pressure cylinders, located in the exhaust-chamber; and a chamber inclosing the high and low pressure cylinders, the valve for the high-pressure cylinders and the exhaust-chamber, and forming a steam-space around them, substantially as specified.
